UNITED STATES PATENT OFFICE

142,631

DESIGN FOR A GARMENT HANGER

Edward Percy Elston, Bradmore, Wolverhampton,
England

Application April 6, 1945, Serial No. 118,871
In Great Britain November 24, 1944

Term of patent 14 years

(Cl. D80—8)

To all whom it may concern:

Be it known that I, Edward Percy Elston, a subject of the King of Great Britain, residing at 20, Willow Road, Bradmore, Wolverhampton, in the county of Stafford, England, have invented a new, original, and ornamental Design for Garment Hangers, of which the following is a specification, reference being had to the accompanying drawing, forming part thereof.

The drawing shows a perspective view of a garment hanger of my new design.

I claim:

The ornamental design for a garment hanger, as shown.

EDWARD PERCY ELSTON.
